CAKE PACKAGE OR THE LIKE

Tracy C. Weltmer, Kansas City, Mo., assignor,
by mesne assignments, to Interstate Bakeries
Corporation, Kansas City, Mo., a corporation of
Delaware

Application October 14, 1936, Serial No. 105,453

1. Claim. (Cl. 206—44)

This invention relates to cake package or the like, of the type in which the cake or other article is visible while protected against mutilation or exposure to the air.

5 An object of the invention is to provide a low-cost package which will be at the same time sturdy and will display the cake conspicuously so as to enforce its attractiveness to the prospective purchaser.

0 Other objects and advantages will be apparent from the following description taken together with the accompanying drawing, in which—

Figure 1 is a perspective view of the frame and pad for my improved package;

Figure 2 is a fragmentary section taken on the line 2—2 of Fig. 1 with a cake partially shown in broken lines and a closure for the package added;

Figure 3 is a perspective view of my improved frame alone.

Referring to the illustrative construction shown in the drawing, my improved frame 10 is advantageously formed of a continuous wire extending for a part of its length as at 11 which is then bent outwardly as at 12, and then bent for part of its length as at 13 right-angularly to both the parts 11 and 12. It is again bent right-angularly for a part of its length as at 14 and again at 15, this latter part being parallel to the part 13. The bend 16 is similar to the bend 12 but inwardly directed and the part 17 is parallel to the part 11. At the end of the part 17 the part is again bent as at 18, this time outwardly, and the part 19 is bent right-angularly to both the parts 17, 18 and parallel to the parts 13 and 15. The part 20 is bent right-angularly to the part 19. The part 21 is again parallel to the parts 13, 15 and 19. At its extreme end the wire is bent at 22 inwardly, parallel to the part 12 and is joined, as by brazing or the like, as at 23, to the end of the part 11. Thus the wire is bent to form a closed loop and is also bent intermediately at intervals of its length to form alternate oppositely facing U-shape frame portions together forming a parallelopiped frame. As shown, the two oppositely disposed parallel lengths of the wire, in this instance 11 and 17, being inwardly offset, provide support for a cake pad 24 which is desirably formed of cardboard or the like and which is adapted to support a bakery product such as the cake partially indicated in broken lines as at 25, Figs. 1 and 2.

In practice the cake is placed upon the pad 24 while the icing, for example, on the cake is still unsolidified, and the solidification of the icing forms a bond as at 26 between the cake and the pad which prevents casual displacement of the cake on the pad.

In order to more conspicuously display the cake in the package and thus render it more attractive to the prospective purchaser the pad 24 is desirably elevated at its center above its margins 27 which rest upon the wire portions 11 and 17, an offset 28 extending around the pad inwardly spaced from its margin 27, thus forming an upwardly directed recess in the bottom of the pad and elevating the cake above the margin as clearly shown in Fig. 2.

In order to prevent casual displacement of the pad with respect to the wire frame, the pad and wire may have interlocking engagement, as for instance the corners of the pad may be notched as at 29 to receive the wire frame, the pad being preferably just large enough to snugly fit the frame.

It will be understood, of course, that the frame is large enough to clear the cake 25 at all points so that when a closure such as a Cellophane wrapper 30 is wrapped around the article so far described, and sealed, the wrapper is out of contact with the cake so as to prevent mutilation of the cake while at the same time the cake is sealed against exposure or handling, while still being fully visible to the prospective purchaser.

Having described my invention, I claim:

A cake package or the like embodying a cardboard pad having margins in one plane and a center portion offset, a single continuous length of wire bent to form a closed loop and also bent intermediately to form alternately oppositely facing U-shape portions together defining a rectangular parallelopiped, portions of the wire being inwardly offset toward the center of the parallelopiped by substantially right-angle return bends to provide a substantially horizontal support having parts of the wire extending in four directions in a single plane, said support receiving margins of said pad thereon while the offset portion of the pad projects further into the parallelopiped and being wholly within the parallelopiped while leaving the parallelopiped rectangular, corners of said pad being notched to receive said return bends.

TRACY C. WELTMER.
